UNITED STATES PATENT OFFICE.

JOSEPH LOEB, OF CHICAGO, ILLINOIS, ASSIGNOR TO THE COSMOPOLITAN INCANDESCENT GAS LIGHT COMPANY, OF SAME PLACE.

MANTLE-SUPPORT.

SPECIFICATION forming part of Letters Patent No. 663,127, dated December 4, 1900.

Application filed June 19, 1900. Serial No. 20,848. (No model.)

To all whom it may concern:

Be it known that I, JOSEPH LOEB, a citizen of the United States, residing at Chicago, in the county of Cook and State of Illinois, have invented a new and useful Improvement in Mantle-Supports, of which the following is a specification.

My invention relates to devices for supporting delicate incandescent mantles during transportation and use.

My primary object is to greatly simplify and cheapen such devices and at the same time lessen the danger of breakage during packing or unpacking of the individual mantles.

The preferred embodiment of my invention is illustrated in the accompanying drawings, in which—

Figure 1 is a perspective view of a mantle and the supporting-standard therefor; Fig. 2, a similar view of the gauze or spreader cap employed; Fig. 3, a similar view of the parts shown in Figs. 1 and 2, here shown partially assembled; Fig. 4, a similar view of said parts fully assembled; Fig. 5, a similar view of a casing-cap employed; Fig. 6, a similar view of the remainder of the casing; and Fig. 7 a broken vertical section showing the mantle, its standard, and the gauze cap inclosed 30 within the casing for transportation.

A represents a casing provided with an end a , which need not be removable, and with an end cap a' , which is removable and bears on its inner surface a centrally-disposed seat or base a^2 for the gauze cap.

B represents a gauze cap removably connected with said base, as by telescoping with and frictionally engaging the same.

C represents a mantle-standard, preferably formed from stiff wire and having at its lower end a horizontally-disposed gauze cap engaging the unclosed curved part b and at its upper end a mantle-supporting hook b' , and D represents a mantle supplied in the process of manufacture with a supporting-loop c .

The part B is preferably provided with the circumferential corrugations d , d' , and d^2 , the two former of which afford between them

a groove for receiving the spring clamping part b of the standard C. The end cap a' 50 preferably has the externally-located flange f , which receives the lower end of the casing, and to prevent accidental removal a sealing-strip f' is provided, the ends of which project beyond the edge of the flange f and are 55 cemented to the casing-body.

The method of use will be readily understood from the foregoing description. The hook b' engages the mantle-loop, the base of the mantle fits comparatively loosely over the 60 upper end of the gauze cap, the part b clampingly engages the gauze cap at the groove between the rings d d' , and the lower end of the gauze cap fits snugly over the base or seat a^2 in the casing-cap a' . The parts last 65 mentioned are assembled, and the casing is then placed in position inclosing the mantle and supporting parts, the flange f receiving the lower end of the casing. The ends of the strip f' are then cemented to the casing-body 70 and the mantle is ready for shipping.

When the mantle is to be used, the ends of the strip f' are severed and the casing lifted from the end cap, the flange f serving at this time as a means for holding the end cap 75 firmly. The gauze cap is then lifted from its seat, carrying with it the standard and mantle. The gauze cap is then applied to the burner in the usual manner.

The casing is commonly of pasteboard, and 80 the part a^2 may be of cork or like material.

Changes in minor details of construction within the spirit of my invention may be made.

What I claim as new, and desire to secure 85 by Letters Patent, is—

1. In a device of the character described, the combination of a casing, a removable end cap therefor provided on its inner surface with a gauze-cap seat and having an external 90 flange f receiving the casing, a sealing-strip projecting above said flange, a gauze cap removably supported on said seat, and a mantle-standard supported by said gauze cap, substantially as and for the purposes set forth. 95
2. In a device of the character described,

the combination of a casing, a removable end cap therefor provided on its inner surface with a gauze-cap seat, a gauze cap removably supported on said seat and provided with a circumferential groove, and a mantle-standard provided at its upper end with means for connection with a mantle and having at its

base an unclosed clampingly-acting curved part *b* engaging the gauze cap at said groove, substantially as and for the purpose set forth.

JOSEPH LOEB.
